UNITED STATES PATENT OFFICE.

SAMUEL T. FIELDING, OF PILOT MOUND, IOWA.

STAPLE PULLER.

Application filed March 22, 1927. Serial No. 177,343.

The object of my invention is to provide a staple puller of simple, durable and inexpensive construction, which is formed of a single piece of stock material and provided 5 with a pointed member adapted to be driven into the post in which a staple is mounted, so that the pointed end may be caused to engage the inner face of the article which is being supported by the staple, said pointed end being 10 so arranged that the main body portion of the puller may be used as a lever for removing the staple after the point has been inserted by simply swinging the body portion through an angular path.

15 A further object is to provide in a staple puller improved means whereby the handle of the puller may be more readily gripped to prevent the same from slipping through the operator's hand.

20 A further object is to provide a staple puller having a staple pulling member at one end and a claw at its opposite end for stretching fence wire and the like, the central portion of the puller being provided with a 25 bulged portion to prevent the handle from slipping on the post while the stretching takes place.

My invention consists in the construction, arrangement and combination of the various 30 parts of the device, whereby the objects contemplated are attained, as hereinafter more fully set forth, pointed out in my claim, and illustrated in the accompanying drawings, in which:

35 Figure 1 is a top plan view of my improved staple puller.

Figure 2 is a side elevation of the same.

Figure 3 is a detail sectional view taken on the line 3—3 of Figure 2.

40 Figure 4 is a side elevation of fence post having a fence wire stapled thereto, showing the manner in which my improved staple puller is applied to remove the staple.

My improved staple puller is formed of a 45 single piece of stock material, preferably a hexagonal bar 10. One end of the bar 10 is formed into a laterally extending portion 11 which is rebent and doubled upon itself to form a second laterally extending portion 12. The member 12 terminates in a tapered and pointed member 13. The member 13 is curved inwardly in the manner shown in Figure 2, with the pointed end of the said member resting in a plane extending substantially 50 midway between the members 11 and 12. The portion connecting the members 11 and 12 is

flattened at 14, the surface of the flattened portion being substantially at right angles to a plane lying between the members 11 and 12, and provides means for receiving the blow 60 of a hammer or similar article for causing the pointed end 13 to enter a post 15 or similar article, in the manner illustrated in Figure 4, to cause the pointed end 13 to enter between the wire 16 and the said post. The 65 member 13 is also driven between the prongs of the staple 17. The handle member 10 is then rotated through an angle causing the outer curved surface of the member 13 to engage the post 15 and the staple is removed 70 from said post.

The body portion 10 is provided with a laterally extending bulged or bent portion 18, which serves as a handle portion for the body portion 10. The transverse portions 19 prevent the operator's hand from slipping longitudinally of the body 10 while the staple puller is being operated. The free end of the body portion 10 is flattened at 20, said flattened portion being bifurcated to form 80 a claw for pulling nails or engaging the barbs 21 of the wire 22 when the tool is being used as a wire stretcher, in which case the post upon which the wire is mounted is caused to enter the bulged portion 18 to prevent the 85 body portion 10 from moving longitudinally. The free end of the body portion 10 may then be rotated about the post in an anti-clockwise direction as shown in Figure 2, causing tension to be applied to the wire 22.

90 Thus it will be seen that I have provided a staple puller of simple, durable and inexpensive construction, which is very convenient either for pulling staples or stretching wire, and which is provided with means for preventing the operator's hand from slipping longitudinally of the body portion while it is being used as a staple puller, and to act as means for preventing longitudinal movement of the said body portion when applied to a 100 post and operated as a wire stretcher.

By looping the staple pulling end of the body portion, I have provided a suitable end for receiving the blow of a hammer or other article. By closing the looped portion, by causing the members 11 and 12 to be supported adjacent to each other, I have considerably reinforced the curved portion, and at the same time enabled the pointed end of the member 13 to lie in a plane substantially 105 perpendicular to the handle member, and at the same time providing a suitable curved 110

portion for the outer surface of the member 13 to act as a fulcrum while the device is being used as a staple puller. By this arrangement it will be seen that any blow on the surface 14 will be in direct alinement with the pointed end of the member 13.

I claim as my invention:

A staple puller comprising a body portion formed of stock material of uniform diameter, one end of said body portion being bent

laterally and rebent upon itself with the overlapping portion adjacent to the laterally extending portion, with the free end of said overlapping portion tapered and curved slightly inwardly, the curved portion connecting the overlapping portions being provided with a flattened face, said flattened face being perpendicular to a plane between said overlapping portions. 15

SAMUEL T. FIELDING.
